UNITED STATES PATENT OFFICE.

RUDOLPH R. BUEHLER, OF PHILADELPHIA, PENNSYLVANIA, ASSIGNOR TO
THE PHILADELPHIA HARDWARE AND MALLEABLE IRON WORKS, OF
PENNSYLVANIA.

REGISTER OR VENTILATOR.

SPECIFICATION forming part of Letters Patent No. 629,336, dated July 25, 1899.

Application filed March 18, 1899. Serial No. 709,583. (No model.)

To all whom it may concern:

Be it known that I, RUDOLPH R. BUEHLER, a citizen of the United States, residing in the city and county of Philadelphia, State of Pennsylvania, have invented a new and useful Improvement in Registers or Ventilators, which improvement is fully set forth in the following specification and accompanying drawings.

My invention relates to registers or ventilators; and it consists in an improved construction of indicator plate or wheel therefor whereby the opened or closed condition of the register or ventilator may be readily ascertained, said plate having openings therein and being supported upon the center of the face-plate, said center being stationary and slotted or provided with openings to conform to the slots or openings in said indicator wheel, so that when the slots register there is an indication of the open condition of the register or ventilator and when the wheel closes the slots at the center of said face-plate the closed condition of the apparatus is indicated, the face of said indicating-wheel being different from that of the stationary center either in shape, color, or configuration, so that its exposure through the slots of the center will readily indicate the opened or closed condition of the register.

It further consists of novel details of construction, all as will be hereinafter fully set forth, and particularly pointed out in the claims.

Figure 1 represents a plan view of an indicating plate or wheel for a register or ventilator embodying my invention. Fig. 2 represents a section on line xx , Fig. 1. Figs. 3 and 4 represent plan views of the front and rear of the central portion of the register, showing the construction and manner of supporting the indicating plate or wheel and also illustrating the open and closed condition of said register. Fig. 5 represents, on an enlarged scale, a perspective view of the spring seen in Fig. 2. Fig. 6 represents, on a reduced scale, a perspective view of the inner surface of the indicator-wheel and the adjacent recessed bar, the parts being shown in detached position.

Similar letters of reference indicate corresponding parts in the figures.

Referring to the drawings, A designates the face-plate of a register or ventilator, the central portion B thereof being stationary and provided with the solid portions C, intermediate of or alternating with which are the openings D.

E designates a stud or journal, to which is secured the indicating plate or wheel F, which is provided with solid and slotted portions G and H, respectively, of the same shape and number as the solid respective and slotted portions C D of the central stationary portion of the face-plate, said indicating plate or wheel having knobs or finger-pieces J projecting therefrom through the face-plate, whereby said wheel can be readily manipulated.

K designates a coil or other suitable spring, which is seated in the recesses or sockets K and K² in the face-plate A and indicator-plate F, respectively, said spring being compressed in said sockets, whereby all improper motion and unpleasant rattling of the parts are prevented, as is evident.

L designates lugs attached to the rear portion of the indicating wheel or plate F, said lugs being adapted to engage the arm M, which projects from a bar or frame N, as best seen in Fig. 3, said bar or frame being provided with the lugs P, Q, and R, which are adapted to engage suitable portions of the rotatable shutters or deflectors S, T, and U, which latter are mounted in suitable bearings V, W, and X in the annular or other shaped frame Y, to which the face-plate A is secured.

The operation is as follows: When the parts appear as seen in Figs. 1 or 2, it will be apparent that the register or ventilator is open, since the openings D and H in the center stationary plate and the rotatable indicating wheel or plate behind it are in alinement. If the finger-piece J be now manipulated in the proper direction, the parts will be caused to assume the position seen in Fig. 4, from which it will be apparent that the solid portions G of the rear wheel F will be directly behind or alining with the open portions D of the central portion of the face-plate, wherefrom it will be indicated at a glance that the register is closed.

It will of course be understood that the

solid portions G, which appear visible through the slots or openings D when the device is closed, as seen in Fig. 4, can be painted or otherwise colored or marked, so that the opened or closed position of the device can be readily perceived.

The engagement of the lugs L with the arm M will cause the frame or bar N to be reciprocated at the proper intervals, and by reason of the intermediate connections the plates or blades S, T, and U are actuated at the proper intervals, as is evident.

A' designates a recess in that portion of the bar N which is contiguous to the boss B' on the inner surface of the indicating-wheel F, said recess being guided by said boss, which latter serves to limit the movement of the bar N, as is evident.

It will be evident that slight changes may be made by those skilled in the art which will come within the scope of my invention, and I do not therefore desire to be limited in every instance to the exact construction I have herein shown and described.

Having thus described my invention, what I claim as new, and desire to secure by Letters Patent, is—

1. The combination of a face-plate having a stationary slotted central portion, an indicating wheel or plate rotatably mounted adjacent to said face-plate, said indicating-plate being provided with solid and open portions respectively, which are adapted to be turned into and out of alignment with the openings through said face-plate and to thus indicate the opened and closed condition of the register, a bar operated by said wheel and having a recess, a boss on said wheel engaging said recess, and operating connections between the bar and the register-shutters.

2. In a register or ventilator, a face-plate, an indicating wheel or plate mounted there-

upon and provided with open and solid portions respectively, conforming to the open and solid portions in the stationary central portion of said face-plate, lugs on said indicating-wheel, a bar suitably supported, a recess in said bar, a boss on said wheel engaging said recess an arm projecting from said bar and engaged by said lugs, and shutters or deflectors actuated by said bar.

3. In a register, a face-plate having a stationary central portion, and provided with a series of slots, an indicating wheel or plate rotatably supported adjacent thereto and provided with a series of slots, annular recesses in said face-plate and wheel located in proximity to each other, a suitable spring seated in said recesses and adapted to prevent rattling and improper movement of the parts when operated, lugs on said wheel, a bar having an arm engaging said lugs, a recess in said bar, a boss on said wheel engaging said recess, and shutters actuated by said bar.

4. In a register, a face-plate having a stationary central portion provided with a series of slots, an indicating wheel or plate rotatably supported adjacent thereto and also provided with a series of slots, annular recesses in said face-plate and wheel located in proximity to each other, a suitable spring seated in said recesses and adapted to prevent rattling and improper movement of the parts, lugs on said wheel, a bar having an arm engaging said lugs, a recess in said bar, a boss on said wheel engaging said recess, the terminus of the latter contacting with said boss when said bar is in its extreme position, shutters rotatably supported and connections common to said shutters and to said bar.

RUDOLPH R. BUEHLER.
